ROTARY TABLE-TYPE MILLING MACHINE Sadayoshi Sakurai, 830 Sukenobu-cho,
Hamamatsu, Japan

Filed Oct. 15, 1971, Ser. No. 189,799

Term of patent 14 years

Int. Cl. D15—09

U.S. Cl. D54—14 A

FIG. 2

FIG. 1

FIG. 4

FIG. 1 is a front perspective view of a rotary table-type milling machine according to my new design;

FIG. 2 is a rear perspective view thereof;

FIG. 3 is a right side view thereof;

FIG. 4 is a left side view thereof; and

FIG. 5 is a top plan view thereof.

I claim:

The ornamental design for a rotary table-type milling machine, substantially as shown.
